UNITED STATES PATENT OFFICE.

BENJAMIN F. HIGGINS, OF NEOGA, ILLINOIS, ASSIGNOR OF ONE-HALF TO
DANIEL W. CHAMBERLIN, OF PARADISE, ILLINOIS.

WEATHER-STRIP.

SPECIFICATION forming part of Letters Patent No. 632,310, dated September 5, 1899.

Application filed January 13, 1899. Serial No. 702,092. (No model.)

To all whom it may concern:

Be it known that I, BENJAMIN F. HIGGINS, a citizen of the United States, residing at Neoga, in the county of Cumberland and State 5 of Illinois, have invented a new and useful Weather-Strip, of which the following is a specification.

The invention relates to improvements in weather-strips.

10 The object of the present invention is to improve the construction of weather-strips and to provide a simple, inexpensive, and efficient one adapted to be readily mounted on a door and capable of operating automatically as the door opens and closes, to elevate itself for clearing the carpet, and to depress itself so as to fit tightly against the door-sill for effectually excluding air.

15 The invention consists in the construction 20 and novel combination and arrangement of parts hereinafter fully described, illustrated in the accompanying drawings, and pointed out in the claim hereto appended.

25 In the drawings, Figure 1 is a perspective view of a weather-strip constructed in accordance with this invention and shown applied to a door, the latter being closed. Fig. 2 is a similar view of a portion of the weather-strip and the door, the former being raised.

30 Fig. 3 is a detail perspective view of the adjustable guide. Fig. 4 is a similar view of one of the end plates of the weather-strip.

35 Like numerals of reference designate corresponding parts in all the figures of the drawings.

1 designates a hinged weather-strip constructed of sheet metal or other suitable material, provided at its upper edge with a circular or cylindrical bead or roll 2, which fits with- 40 in a corresponding bead 3 of an attachment-strip 4, which is secured to the outer face of a door 5 by screws or other suitable fastening devices. By this construction the weather-strip is hinged to the door and is adapted to

45 swing upward and downward. It is held against longitudinal movement in the bead 3 by end plates 6, arranged at the ends of the attachment-strip 4 and provided with shanks or stems interposed between the attachment- 50 strip and the door and retained in place by the fastening devices of the former.

When the door is opened, the weather-strip is automatically elevated by a pair of springs 7, secured at their upper ends between the attachment-strip and the door and having 55 their lower portions curving outward and engaging the lower face of the hinged weather-strip; but instead of employing a pair of springs either one or more than two may be provided.

60 When the door is closed, the hinged weather-strip is directed into engagement with a keeper 8 by an adjustable guide 9, mounted on a pivoted block or piece 10 at one side of the door-casing. The block or piece 10, which 65 tapers toward its lower end to provide an inclined inner face 11, is secured to the door frame or casing by a screw 12 or other suitable fastening device which is adapted to permit the tapering piece or block and the 70 adjustable guide to be swung backward out of the way when it is not desirable or necessary for the weather-strip to fit tightly against a door-sill. The guide 9 consists of a strip of metal having its upper end curved to form 75 a handle and provided between its ends with a longitudinal slot 13, in which are arranged screws 14, whereby the guide is secured at the desired adjustment for operating the 80 weather-strip properly.

75 The keeper consists of a short plate secured to the sill, as shown, and having its inner or upper end bent downward to engage the weather-strip, and it is adapted to hold the latter tightly against the sill and relieve the 85 guide of strain. The lower end of the adjustable guide, which is arranged at an angle to the pivoted block or piece, forms a cushion and is adapted to engage the weather-strip yielding; but as it is of much greater 90 strength than the springs which support the weather-strip at an elevated position it is capable of holding the weather-strip firmly against the sill to direct it into engagement with the keeper.

95 The invention has the following advantages: The weather-strip, which is simple and comparatively inexpensive in construction, is strong and durable and adapted to be readily applied to a door, and it is capable of operating automatically to clear the carpet when the door opens and to fit tightly against the 100

sill when the door is closed. The adjustable guide, which is mounted on the door-frame, is adapted to be raised and lowered, and the tapering block or body, which is secured at its upper end by a single fastening device, is adapted to permit the guide to be swung backward out of the way when it is not necessary for the weather-strip to fit tightly against the sill. The screw which permits 10 this pivotal movement of the tapering block or body is adapted to hold the same sufficiently firmly in position to avoid being pushed aside by the weather-strip.

Changes in the form, proportion, and minor 15 details of construction may be resorted to without departing from the spirit or sacrificing any of the advantages of this invention.

What is claimed is—

In a device of the class described, the com-

bination with a weather-strip designed to be 20 hinged to a door, of a block or body 10 pivoted at its upper end and adapted to be swung aside to throw the device out of operation, a stationary keeper mounted on the sill and arranged to be engaged by the weather-strip 25 when the same is swung downward, and an adjustable guide mounted on and carried by the block, forming a cushion and adapted to be engaged by the weather-strip, whereby the same is swung downward, substantially 30 as described.

In testimony that I claim the foregoing as my own I have hereto affixed my signature in the presence of two witnesses.

BENJ. F. HIGGINS.
